UNITED STATES PATENT OFFICE

CHARLES F. BALL, OF MILWAUKEE, WISCONSIN, ASSIGNOR TO CHAIN BELT COMPANY, OF MILWAUKEE, WISCONSIN, A CORPORATION OF WISCONSIN

LOCK FOR TILTING DRUM CONCRETE MIXERS

Application filed December 11, 1928. Serial No. 325,347.

This invention relates to concrete mixers, and more especially to mixers of the tilting drum type, and has for its principal object the provision of a simple and effective means for locking the drum against tilting movements in either its mixing or its discharge position.

In one form of the well known tilting drum mixers the tilting movements are accomplished through a train of gears which may be actuated through the medium of a hand wheel, and the present invention contemplates the employment of one of the gears of the actuating gear train as a means for locking the drum against tilting movement at certain times. This is preferably effected through so mounting one of the gears of the train that it may be moved axially to bring its teeth into or out of engagement with a stationary stop member carried by the frame of the machine, it being understood of course that when the gear teeth are in engagement with the stop member rotation of the gear will be prevented with consequent locking of the drum against tilting movements. The ends of the gear teeth are preferably beveled in order to facilitate their engagement with the stop member.

With the above and other objects in view, which will appear as the description proceeds, the invention consists of the novel details of construction, combinations and arrangements of parts more fully hereinafter described and particularly pointed out in the appended claims.

Referring to the accompanying drawings forming a part of this specification in which like reference characters designate like parts in all the views:

Fig. 1 is a fragmentary side elevational view of a concrete mixer of the tilting drum type illustrating the present invention applied thereto.

Fig. 2 is a detail front elevational view of the stationary locking member.

Fig. 3 is an edge elevational view of the locking member as seen from the left of Fig. 2.

Fig. 4 is an enlarged fragmentary sectional

detail view taken approximately on the plane indicated by the line 4-4 of Fig. 2.

Fig. 5 is an enlarged assembled sectional view of the locking mechanism taken approximately on the plane indicated by the line 5-5 of Fig. 1, and

Fig. 6 is a detail front elevational view of the slidable pinion or gear which engages the stop member shown in Figs. 2 and 3 for performing the locking operation.

In the said drawings the numeral 10 indicates generally the frame of a concrete mixer in which is journaled for tilting movements the mixing drum 11. The drum is adapted to be tilted about its pivots 12 by means of a gear wheel 13 which is engaged by a pinion or gear 14, which in the present instance is of peculiar construction and is best illustrated in Figs. 5 and 6. That is to say the said pinion comprises a hub portion 15 upon which the gear teeth 16 are cut and which is provided at one end with a flange 17 which may be substantially triangular shape as shown in Fig. 6. The back face of the flange 17 is recessed as at 18, and the flange is secured as by bolts 19 to the hub 20 of a hand wheel 21, by means of which the gear may be rotated to cause the tilting movements of the drum.

Secured to the frame 10 of the mixer at a suitable point is a stop plate or member 22, which may be provided with elongated openings 23 for receiving the securing bolts by means of which it is attached to the frame, the purpose of the said elongated openings being to permit of arcuate adjustment of the member on the frame relative to the gear 14. This adjustability provides means for bringing the recesses 32 of the member 22, to be later described, into proper position to receive the teeth 16 of pinion 14 when the drum is at its proper mixing or discharging angle.

The member 22 is provided with a bore 24 which receives a pin or stud 25, provided with an enlarged bearing portion 26, upon which the pinion 14 is rotatably and slidably mounted, and the said pin is retained in position in the bore 24 of the stop plate or member 22 by suitable locking nuts 27, as shown in Fig. 5. The opposite projecting end of the stud 25 is threaded as indicated at 28, which threads 100

are engaged by a nut 29 having a flange 30 which is received in the recess 18 of the pinion 14, as shown in Fig. 5. As will be clear from the said figure the flange 30 is positioned between the flange portion 17 of the pinion and the face of the hub 20 of the hand wheel 21, whereby there is provided a connection between the nut 29 and the assembled pinion and hand wheel which permits of relative rotary motion between the nut and the other parts, but which causes any axial movement of the nut to be transmitted to the pinion and wheel. The nut 29 is further provided with the rigid handle 31 by means of which it may be manually rotated as will be more fully described below.

The face of the stop plate 22 is provided with a plurality of recesses 32, concentrically arranged around the bore 24, which recesses are of such shape and so positioned as to receive the end portions of the teeth 16 of the gear or pinion 14. These end portions are preferably bevelled as indicated at 33 to facilitate the entry of the said teeth into the recesses as will be readily understood.

The operation of the invention will be clear from the foregoing, but it may be briefly summarized as follows:

In Fig. 1 the mixing drum 11 is illustrated in its material-receiving and mixing position. In order to maintain the drum in this position against any possibility of tilting about its pivots 12 during the charging and mixing operation, the handle 31 of the nut 29 is manually operated to rotate the nut in the proper direction to cause the latter to move axially inwardly upon the stud 25, which motion will, through engagement of the nut with the pinion 14, cause an axial movement of the latter together with the hand wheel 21, so as to bring the bevelled end portions 33 of the pinion teeth 16 into the recesses 32 of the stop plate 22. It thus follows that the pinion 14 is locked against rotation, and since its teeth are still in engagement with the teeth of the gear 13, the latter gear is also locked and the drum 11 carried by the pivots 12 on which the gear 13 is mounted is likewise locked. The parts are now in the positions illustrated in Fig. 5 and remain in such positions until the mixing operation is completed, whereupon by a reverse movement of the handle 31 the nut 29 will be moved toward the left as viewed in Fig. 5, thereby withdrawing the teeth of the pinion 14 from engagement with the recesses 32 of the stop plate, whereupon the said pinion may be rotated by means of the hand wheel 21 and its motion transmitted through the gear 13 to the drum 11, which will be tilted in a counterclockwise direction, as viewed in Fig. 1, to its discharging position. The drum may, if desired, be locked in such discharging position, or in fact in any position intermediate the discharging

and the mixing positions, by simply manipulating the handle 31 as above described.

While one form of the invention has been illustrated and described, it is obvious that those skilled in the art may vary the details of construction as well as the precise arrangement of the parts, without departing from the spirit of the invention, and therefore it is not wished to be limited to the above disclosure, except as may be required by the claims.

What is claimed is:

1. A lock for the tilting drums of concrete mixers which are provided with means including a train of constantly meshed gears for tilting said drum, comprising a recessed stop member adapted to be secured to the frame of the mixer; and screw threaded means for moving one of said gears to bring its teeth into and out of engagement with the recesses of said stop member to prevent and permit tilting movements of said drum said gear remaining in either engaged or disengaged position at will.

2. A lock for the tilting drums of concrete mixers which are provided with means including a train of constantly meshed gears for tilting said drum, comprising a stop plate having a plurality of recesses, adapted to be secured to the frame of the mixer; a stud constituting a journal for one of said gears projecting from said plate and provided with a threaded end; and a nut coaxial with the threaded end of said stud for sliding said gear thereon to bring its teeth into and out of engagement with the recesses of said stop plate and thereby prevent or permit the tilting movement of said drum said gear remaining in either engaged or disengaged position at will.

3. A lock for the drums of concrete mixers of the tilting-drum type which are provided with means including a gear for tilting said drum, comprising a stop plate having a plurality of recesses, adapted to be secured to the frame of the mixer; a stud having a threaded portion, projecting from said plate; a pinion having a flange rotatably and slidably mounted on said stud, with its teeth engaging those of said drum-tilting gear; a manually operable member having a hub secured to the flange of said pinion; and a flanged nut engaging the threaded portion of said stud, the flange of said nut being disposed between said hub and the flange of said pinion, whereby it may cause the sliding of said pinion upon said stud to bring the end portions of its teeth into and out of engagement with the recesses of said stop plate to prevent or permit the tilting movement of said drum.

4. A lock for the tilting drums of concrete mixers which are provided with means for tilting said drum including a constantly meshing train of gears and means for rotating one of said gears, comprising a recessed stop

member secured to the frame of the mixer; and means independent of said gear-rotating means for positively moving one of said gears axially in either direction to bring its teeth into and out of engagement with the recesses of said stop member, said gear remaining in either engaged or disengaged position at will, and constantly meshed with its companion gear.

10. In testimony whereof I affix my signature.
CHARLES F. BALL.
